UNITED STATES PATENT OFFICE.

ORREN ALLEN, OF DENVER, COLORADO.

FLOTATION ORE-CONCENTRATING APPARATUS.

1,250,938.

Specification of Letters Patent. Patented Dec. 25, 1917.

Application filed October 12, 1916; Serial No. 125,219.

To all whom it may concern:

Be it known that I, ORREN ALLEN, a citizen of the United States of America, residing at the city and county of Denver and 5 State of Colorado, have invented a new and useful Flotation Ore-Concentrating Apparatus, of which the following is a specification.

My invention relates to a new continuous 10 centrifugally operating oil flotation ore concentrating apparatus; and the objects of my invention are:

First, to provide an oil flotation concentration apparatus for ores in which the ore 15 pulp and oil and air are kept in constant and continuous movement in the apparatus while being mixed and commingled together, and in which there are no corners or spaces where the colloidal matter or mineral particles can 20 collect and pack.

Second, to provide an oil flotation concentration apparatus for ores in which the ore pulp and oil and a supply of air are circulated continuously and automatically by 25 mechanism that creates a suction action by centrifugal force, that mixes and commingles these elements together and keeps them in constant and rapidly flowing action and motion, until they flow into the concentrates separating compartments of the apparatus. And

Third, to provide a positively feeding and operating ore pulp treating oil flotation ore concentrating apparatus of large tonnage 35 capacity that is simple, compact and durable in construction and that can be easily taken apart when it is desired to clean the same and put together again by unskilled labor, and that draws air into it by suction.

10 I attain these objects by the mechanism illustrated in the accompanying drawings, in which:

Figure 1, is a plan view of the improved oil flotation ore concentrating apparatus.

5 Fig. 2, is a vertical, longitudinal sectional view on the line 2—2 of Fig. 1.

Fig. 3, is a vertical, transverse sectional view on the line 3—3 of Fig. 1.

Fig. 4, is a side view partly in section, 0 showing one of the ore-pulp-receiving cylinders, and a portion of the adjoining mixing cylinder, also the radial blades which are supported around said mixing cylinder.

Fig. 5, is a vertical, transverse sectional view on the line 5—5 of Fig. 4.

Fig. 6, is a horizontal sectional view

through a portion of one of the receiving cylinders and the adjacent partition, showing the manner in which the dividing blades and their supporting disks are pressed 60 against one end of each receiving cylinder, and are thereby held stationary.

Fig. 7, is a vertical, longitudinal sectional view of one of the rotary mixing cylinders.

Fig. 8, is a front view of one of the rings 65 which are clamped against one of the blade holding plates of each pair, in the manner shown in Fig. 6.

Fig. 9, is an end view of one of the packing boxes and its supporting plate, which 70 forms the closure for one of the end ore circulating compartments. And

Fig. 10 is a side view of one of the combined ore pulp inlet and air inlet pipes for the ore pulp receiving cylinders. 75

Similar letters of reference refer to similar parts throughout the several views.

Referring to the drawings,—

Figs. 1, 2 and 3 represent an apparatus embodying my invention, and in these figures, as well as in some of the remaining figures, the numeral 1 designates the first unit of a multiple unit oil flotation concentrating apparatus.

The numeral 2 designates the second unit, 85 and the numeral 3 designates the third unit. These units are all alike in their manner of receiving, mixing, concentrating, and separating the mineral values from ore pulp to which oil has been added to effect a concentration of the mineral particles that mix with oil and air that have been added to the ore pulp either before the ore pulp is fed into the apparatus or after it is fed into the apparatus, and also a separation by floating 90 95 the concentrated mineral and oil product from the ore pulp into preferably a filter, from which it is either conveyed to further treatment or is shipped to a smelter.

I preferably illustrate my oil flotation concentration apparatus made up into a three unit machine, although if desired only one or two units may be used, or as many units may be added to the three illustrated as it is thought necessary, to effect a satisfactory 100 105 concentration of the mineral values of the ore pulp.

Each of my three oil flotation concentrating units comprises an ore pulp circulating compartment 8, and a settling, concentrating 110 and separating compartment 9.

The three ore pulp, oil and air mixing and

separating units are mounted in a three compartment tank having ends 4 and 5. These compartments are separated from each other by partitions 6 and 7.

- 5 This tank and its ends and the partitions therein that form the mixing and concentrating compartments, may be made of metal or wood, as desired. I preferably however, construct them of wood. Each one of the 10 three sets of compartments forms with the mixing mechanism therein a complete oil flotation and concentrating unit by itself, but they are united into coöperating units to enable a more thorough concentration and separation of the mineral values than one will give.

The ore pulp circulating compartments have their rear end portions sloping down to their vertical end portions, forming an 20 angle-shaped bottom end in each. The separating compartments have their inner walls 10 sloping toward their outer vertical walls 11, which forms an angled bottom end in each, which permits the heavier particles 25 to settle into a narrow space in each, from which it is easily and quickly removed from them, as will be hereinafter clearly described.

The ore pulp, oil and air mixing mechanism of each unit consists of the following 10 instrumentalities, which are all mounted on a rotating shaft 12, that is journaled in hanger bearings 13 at its opposite ends, that are secured to and depend from channel 5 beams 14, that extend across the opposite ends of the tank and rest on columns 15, that project vertically upward from the ground or from suitable foundations or from the floor of a mill. I preferably make these 1 columns however of concrete. There are two sets of these channel beams 14, and the beams of each set are placed back to back with a space between them, and the flanges 16 of the hanger bearings are bolted to their lower flanges 17.

This rotating shaft extends through suitable stuffing boxes 18, that surround the shaft and are secured to the opposite ends of the tank.

These stuffing boxes are provided with flanges 19 and 19^A that are secured to the opposite ends of the tank, and also with lugs 20 that are secured to the under side of cross beams 21, that are secured to channel beams 22 and 23. These beams and channels support the weight of the tank, which is suspended wholly from the beams, and does not rest on anything at any part of its bottom portion. The object of this depending arrangement of the tank with its various compartments is to insure the alinement of the ore pulp mixing and circulating mechanism, in case the wood work of the tank warps badly. The sides of the separating compartments are provided with

plank extensions 24 that are always dry and are provided solely to prevent that portion of each side that is constantly wet with the ore pulp, from warping enough to spring leaks.

70 The two beams 22 and 23 extend along and close to the opposite sides of the tank, which is secured to and supported by them, preferably by being bolted to them.

A third channel beam 25 extends across 75 the ends of the separating compartments, the ends of which are extended as shown at 26 and rest upon the said beams 25 and 23.

The ore pulp is received into unit number 80 1, through a pipe 27, that is preferably provided with a hopper 28 at its upper end, which receives the ore pulp from a stamp or a ball mill or from some other ore crushing or pulverizing machinery, which I do 85 not illustrate, where it is mixed with a sufficient amount of water to form a flowing stream that is called ore pulp. This ore pulp flows to the hopper of the inlet pipe 27 through a launder 29 or other suitable 90 conveyer. The lower end of the ore pulp inlet pipe 27 is threaded to an aperture 30 formed in a receiver 31, which preferably consists of a cylindrical casting that is secured to and is supported dependingly from 95 a cross tie beam 32 by bolts 33. The beam 32 is secured at its ends to the sides of the tank. This cylinder is provided with a semi-circular row of holes 31^A in its top surface, which admit ore pulp to its interior from the circulating compartment 8, as will be more fully described hereinafter.

100 The outer end of this ore pulp receiving cylinder 31 fits into and extends through an aperture formed in the end 5, of the tank, 105 and a hub portion 24 formed on the flange of the adjacent stuffing box 18, extends into the end of the receiver far enough to center the stuffing box and the ore pulp receiving cylinder together concentrically to the rotating shaft.

110 The opposite end of this ore pulp receiving cylinder extends against a ring shaped plate 35, that is held against rotation, as will be presently described.

115 On the shaft with one end close to the adjacent side of the plate 35, a rotating cylinder 36 is mounted. This cylinder comprises an end flange 37, on which a hub 38 is formed that fits on the shaft and is secured thereto, preferably by a pin 39 that extends through the hub and through the shaft. On the circumferential, peripheral edge of this flange, a drum portion 40 that preferably consists of a piece of pipe, is fitted, and is secured thereto preferably by threaded pins 41, that extend through the drum into the casting. The opposite end of the drum fits tightly over a thin flange 42, that forms the opposite 120 end of the cylinder. This end flange is pro- 125

vided with an axial aperture that is enough larger than the shaft to form a circular passageway for the ore pulp from the receiving cylinder, which is drawn through this aperture from the receiving cylinder into this rotating ore pulp, oil and air mixing cylinder.

The peripheral surface of the drum portion 40 of the cylinder is provided with numerous rows of holes 43, throughout its circumference and its length, enough being provided to readily discharge by centrifugal force the ore pulp emulsion as fast as it flows into it from the receiving cylinder, as will be presently described.

15 At the side of the hub end of the cylinder, a ring-shaped plate 44 is placed, that is similar in construction to the plate 35, that is placed between the receiving cylinder and the mixing cylinder. This ring shaped plate 20 fits loosely over the hub of the end flange 37 of the cylinder, and close to the side of its flange 37, but does not bear against it or against the opposite end of the cylinder, as the rings are stationary while the cylinder 25 rotates between them.

These two ring shaped plates 35, 44 are larger in diameter than the mixing cylinder, and their peripheral edges are provided with a circumferential row of radial slots 45, and 30 also with annular grooves 46. These slots 45 are adapted to receive and support between the plates 35 and 44 a circumferential row of ore pulp dividing blades 47. The radial slots 45 are of equal number and 35 size in each plate, and their opposite ends are provided with an inward offset that allows the edge of these blades to be peened or swaged into annular grooves, which acts to rivet the blades to the plates, and the inwardly offset portion extends through the slots 45 and down the inside of these plates a short distance and then across to the opposite site plate, as will be understood by Fig. 6.

The plates 35 and 44 are mounted on the 45 opposite adjacent ends of the ore pulp receiving cylinders of the units 1 and 2, and in order to place and hold them on the ends of these cylinders they are each divided into two equal halves, the diametrical divisional 50 line being placed between two opposite pairs of blades, and in order to hold these plates with their radiating blades concentrically on the ends of these cylinders I provide each half of the plates with three pins. Two of 55 these pins 48 are positioned in a concentric circle, that enables them to rest on the outside peripheral surface of the adjacent ends of these stationary cylinders, while the third pin 48^A is positioned to project into and rest 60 close against the inner peripheral surfaces of these cylinders in order to mount these halves onto the ends of these cylinders after the cylinders are positioned around the driving shaft in the ore pulp holding compartment 65 31 of the unit 1. The adjacent ends of

these two cylinders are each provided with a slot 49 that extends entirely through their shells, and when placing the first half in position between these stationary and the rotating cylinder the inner pin 48^A is 70 passed through this slot into the interior of the stationary cylinders, and then the two outside pins 48 will rest on the outside periphery of these cylinders, and these first placed halves are then turned around on the 75 ends of these cylinders until they are on its under side. The other half of the plates is then placed on the top of these cylinders in the same manner. The two halves of each plate are then united into true concentric 80 circular plates, with the inner edges of their blades fitting closely and concentrically entirely around the rotating cylinder, which rotates within them, and so close to them, that the ore pulp discharged and thrown out 85 by it through its numerous peripheral holes is subdivided into numerous thin sheets as it flows into the body of ore pulp in this ore pulp holding chamber of the first unit.

The baffle blades 47 are placed and secured 90 preferably closer together than the diameters of the holes through the circumference of the mixing cylinder, and the slots in the plates are of a depth that will bring the inner edge of each blade as close to the rotating surface of the cylinder as it will rotate without bearing against them, in order that the ore pulp thrown out of the holes of the rotating cylinder may move radially 95 between each two blades without passing 100 under them.

The ore pulp mixing cylinder is rotated by a belt driven pulley 50, that is mounted on the shaft 12 outside of the end 5 of the tank, and should make preferably about 105 1,200 revolutions per minute. This speed, however, may be increased or diminished to suit different ores.

The pulley is positioned between two depending hangers 13 that firmly support 110 the shaft on opposite sides of it. The ring shaped plates 35 and 44 and their blades 47 are held from rotating by winged screws 51, which are threaded through the hub 52 of a disk 53 that is secured to the opposite side 115 of the partition 7 from the ring plate 44. These ring plates 44 separate the ore pulp circulating compartment of each of the concentrating units from the others in the concentrating tank.

These screws 51 are threaded through the hub 52 of the disk 53 and are extended loosely through the partition 7, in positions to be readily accessible to an operator from the open top of the agitating compartment 125 of each unit, and their ends bear against the adjacent side of a thin disk-shaped ring 54 that surrounds closely the adjacent end of the ore pulp receiving cylinder 55 of unit 2 of my oil flotation concentrating apparatus. 130

This ring disk is provided with a narrow annular lug 56, that projects from its side facing the adjacent blade supporting plate, and when the screws are turned to press against this ring disk its annular lug engages the adjacent side of the flange 44 and forces it and its blades and the flange 35 on the opposite side of the blades against the end of the first unit's ore pulp receiving cylinder 31, and the outer end of this cylinder 31 bears against the circular flange or head of the adjacent stuffing box 18, which flange is bolted to the adjacent end of the tank, thus making substantially tight enough joints between the fixed ore pulp receiving cylinder and the end of the tank and between the rotating ore mixing and centrifugally discharging cylinder and the adjacent ends of both the first unit and the second unit ore pulp receiving cylinders between which this rotating cylinder rotates, to prevent the ore pulp from circulating and lodging between them. Consequently the ore pulp must flow into this rotating cylinder and out through its holes between the blades and into the ore pulp holding chamber 8 of the first unit of my oil flotation machine, from which it flows through one or more apertures 57 formed in the side X of the tank, into the ore pulp settling and concentrates collecting and separating compartment of the unit 1, to the bottom of which a pipe 58 extends, from the ore pulp receiving cylinder 31 of the unit 1.

The rotating ore pulp, oil and air mixing cylinder rotates at such a high rate of speed that it creates a suction force sufficient to continuously draw the ore pulp that is continuously discharging from the circumferential circle of blades into the ore pulp holding chamber, which is kept full from its pointed bottom up to the discharging holes 57 that allow it to flow from this ore pulp circulating compartment into the separating compartment of the unit 1.

The air supply is also drawn into the ore pulp by the suction created by the rotative and centrifugal force actions of the mixing cylinder rotating at a high rate of speed.

The air is admitted to the ore pulp receiving cylinder in the following manner:

A pipe 59 of somewhat larger diameter than the ore pulp feeding-in pipe is threaded to an aperture in the top of the ore pulp receiving cylinder, and the upper end of this pipe extends upward from this cylinder to close to the top of the ore pulp or the water line of the ore pulp, and its end is covered with a screen 59^a of coarse enough mesh to admit the ore pulp which overflows into it and runs down into the ore receiving chamber but fine enough to prevent the oil froth that collects on the top of the ore pulp from flowing into the pipe with the ore pulp,

as this oil froth is a concentrated minerals 65 particles containing froth that moves into the settling spitzkasten compartment and it is not necessary that it be reagitated.

To the top surface of this screen one end of a small pipe 60 is secured by a flange member 61 that is secured to the pipe and to the screen by any suitable means. The upper end of this pipe opens to the atmosphere, and a valve 62 is inserted in the pipe to regulate the flow of air down into the ore 75 pulp receiving cylinder. The action of the unit 1 is as follows:

The ore pulp with which oil is preferably mixed before the ore pulp enters the ore pulp receiving cylinder, which can be effected by flowing a stream of oil of the volume required into the hopper from a tank 63 through a pipe 64, enters the ore pulp chamber and the ore pulp at its top line flowing down also into this cylinder through the 85 screen by gravity and assisted by the suction force of the rotating mixing cylinder, draws the air by suction when the valve is open down into the pipe 59 and through it into the receiving cylinder and from it into its 90 interior. The air drawn down by suction into the pipe encounters innumerable small streams of ore pulp that are continuously flowing through the screen into the pipe from the top of the body of ore pulp, and consequently the inflowing air commingles 95 with the ore pulp flowing into the cylinder 31 through this pipe 59. Then the whole body of ore pulp is drawn by the suction force of the rotating cylinder into the interior of it, and the ore pulp and oil and air are thoroughly mixed and commingled together, and these mixed products are discharged by centrifugal force through the holes in the circumference of the rotating 105 cylinder between the circumferential row of blades 47, which divides it into a circumferential row of thin sheets of ore pulp into the ore pulp in the ore pulp circulating compartment of unit 1, which body of ore pulp is 110 kept in continuous circulation by being drawn from the sloping and pointed bottom portion of this chamber by the suction action of the rotating mixing cylinder through the pipe 58 and the top of the body of ore pulp 115 overflowing into the pipe 59 into the ore pulp receiving cylinder, the inflowing and the mixing centrifugally forcing out and redrawing in and remixing and throwing out action being automatically continuous, especially for the purposes of preventing even the least possible portion of the heavier particles of the ore pulp from settling in the bottom or corners of the ore pulp holding chamber or in any part of its apparatus.

This thorough mixing and commingling of the ore pulp, oil and air causes the air to break up into small bubbles, and the oil to

divide into small drops, and as both have seemingly an affinity for the lighter mineral particles, or the function of attaching themselves to and surrounding the mineral particles, and as the constantly agitated ore pulp flows from the ore pulp circulating compartment through the apertures 57 in the side wall X into the separating compartment, where the ore pulp comes to a slow un-
10. agitated flowing mass that is in substantially such a restful condition that the heavier mineral and the gangue matter sink to the bottom of it and the lighter mineral particles are buoyed up and are floated by the air and
15 oil to the top surface in the form of a frothy mass which gradually floats continuously to and discharges from the discharge lip 65 of the separating compartment and drops into a filtering box 66, which may be of any suit-
20 able construction, from which it may be conveyed away to further treatment or to a bin, which I do not illustrate.

The ore pulp and gangue matter that settle in the bottom of the separating compartment is sucked up through a pipe 67 by the suction action of the centrifugal force of the rotating mixing cylinder of the second unit of the machine.

The second and third units of my oil flotation ore concentrating apparatus are in construction, arrangement and operation just like that of the first unit, and they each contain all of the parts of the first unit except the ore pulp feeding-in pipe and hopper, and the oil supply tank and its pipe, and for this reason a detail description of them is unnecessary. There are however features of coöperative construction, arrangement and operation between the units that are novel and necessary to attain the best results in the concentrating treatment of ores, which features are as follows:

The ore pulp receiving cylinder 55^a of the second and third units and also the hub portion on the flange head 19 of the adjacent stuffing box 18 project through and from the rear end of the tank and the partitions respectively to allow their ends that are adjacent to the rotating cylinders to receive and be connected to the ring-shaped ore pulp dividing blade. The supporting plates 35 and 44 also fit over both ends of the ore pulp receiving cylinders 55 and 55^a of the units 2 and 3 and over the inner end of the hub 55 on the flange 19 at the rear of the third unit, thus forming a close jointed and continuous construction of the ore pulp receiving, mixing, agitating, and circulating mechanism in axial alinement with and concentric to the longitudinal axis of the rotating driving shaft 12 that insures steady, permanent and continuous high speed capacity of the apparatus.

The complete and continuous coöperating

operation of the three units of my oil flotation ore concentrating apparatus, is as follows:

The shaft and the three mixing and centrifugally discharging cylinders are started to rotating at a high rate of speed, preferably not less than about 1200 revolutions per minute. The ore pulp and oil are then turned into the hopper and inlet pipe and they flow into the receiver of the unit 1. The valves 62 of all of the air inlet pipes that enter the screened pipes 59 are also opened and each of the rotating cylinders draws air from the atmosphere through these pipes into the receiving cylinders 31, 55 and 55^a of all three units, and from them into their interiors by suction, which is caused by the high speed centrifugal force action that forces the ore pulp swiftly through the numerous holes throughout their peripheral surfaces.

The ore pulp with the valve controlled and regulated amount of oil and air is sucked from the receiving cylinder 31 of the first unit through the apertures in the top of the receiving cylinder and through the opening in the end flange 42 of the rotating mixing cylinder 36, into the interior of that cylinder. It is subjected to the high rotative speed of that cylinder, and is swirled and mixed and commingled together and the oil and air is disseminated throughout the ore pulp, and the mineral particles attach themselves to the walls of the air bubbles that are formed in the ore pulp. Both the oil and the air and the mineral particles have an affinitive attraction for each other, and will unite in ore pulp when the ore pulp is thoroughly agitated and these elements are given freedom of action.

The high rotative speed of the mixing cylinder 36 of the first unit forces the ore pulp, oil and air swiftly through the holes in its peripheral surface of this cylinder out from its interior between the stationary baffle blades, which divide the ore pulp into numerous streams, a machine of about 300 tons capacity per day being preferably provided with about eighty-eight blades, which makes eighty-eight narrow passageways for the ore to flow through, and through which it is forced to flow swiftly before it mingles with the body of the ore pulp in the circulating compartment 8 of this first unit.

The circulating compartment 8 of this first unit, fills up to the overflowing and discharging line, which we will call the ore pulp water line, instantly after the ore pulp is turned into the machine, and its shaft and mixing cylinders are started to rotating. Consequently the eighty-eight narrow sheets of mixed ore pulp, oil and water are forced into the body of ore pulp in this compartment, and this body of ore pulp is drawn

constantly back into the receiving cylinder 31 through the screen from its water line overflowing portion, and also from the bottom of this compartment through the pipe 58, by the suction pulling force of the centrifugal force of the mixing cylinder 36 of the unit 1, and constantly while this remixing operation is going on, the top portion of the now thoroughly mixed ore pulp, oil and air is overflowing into the separating compartment through the apertures, as fast as it is running into this unit. Constantly the ore pulp in this circulating compartment 8 is drawn back into the receiving cylinder 31 from both its top and bottom portions, and is remixed and passed through the rotating cylinder and between the baffle blades, and the whole body of ore pulp in this compartment is kept in such a rapid circulating motion that it is impossible for any gangue or mineral or colloidal matter of any kind to settle in and lodge or pack in any part of it.

The oil and air mixed ore pulp as it overflows from the circulating compartment into the separating compartment enters a substantially quiet body of ore pulp, and the mineral particles that have not received a sufficient coating of air bubbles and oil to float them together with the gangue matter, settle to the bottom of the separating compartment while the mineral particles that have become sufficiently coated with air bubbles and oil to be floated, rise to the top surface of the ore pulp as concentrates in the form of an oily froth, which is moved by the inflowing body of ore pulp to the discharging lip 65 of this settling, floating and separating compartment, and discharges over the lip 65 and drops preferably into the filter 66, from which the accumulated concentrates are removed from time to time by any suitable means.

The non-floated mineral particles of the ore pulp together with the gangue matter therein, is drawn from the bottom of the separating compartment of the first unit as fast as it settles therein by the suction force of the mixing cylinder of the concentrating unit 2, through the pipe 67 which leads from the bottom of the compartment of the separating compartment to the receiving cylinder 55 of the unit 2, from which it is drawn by the rotating cylinder 36^A, together with air which it sucks in from the valved air and the screened pipes 59 and 60.

This high speed rotating cylinder 36^A of this second unit then agitates, mixes and discharges by centrifugal force the ore pulp through the holes in its peripheral surface, into and between the baffle plates surrounding it and into the circulating compartment 8 of this second unit, from the top and bottom of which the ore pulp is drawn by suc-

tion by this mixing cylinder 36^A of this second unit, through the screened pipe 59 at its water line and the depending pipe 58 into its receiving cylinder and through the holes 31^A in the top of the receiving cylinder into its interior and is again mixed and thrown out again through its holes between the baffle plates again into the body of the ore pulp in the compartment of this second unit, from which it is continuously overflowing into the separating compartment of this second unit, where a settling and floating, separation and concentration of its air bubbles and oil incased mineral takes place, which discharges over the lip of this compartment into the filter 66.

The settling gangue and mineral particles of the ore pulp are sucked up through a pipe 68, from the bottom of the compartment of the separating compartment of this second unit into the receiving cylinder 55^A of the third unit by the high speed rotating cylinder 36^B of this third unit. The receiving cylinder of this third unit is also provided with ore pulp inlet holes 31^A in its top surface and with a screened ore pulp and a valved air inlet pipe and a pipe leading to the bottom of the circulating compartment of this third unit, and the rotating cylinder is also surrounded with baffle plates, consequently exactly the same continuous centrifugal force mixing, agitating, suction, circulating action takes place in the compartment 8 of this third unit as in the first and second units, and the ore pulp overflows continuously into its separating compartment 9 and the same settling, floating and concentrating action takes place and the oil froth concentrates discharge from it into the filter 66. The settling in the compartment of this third unit separating compartment are called tailings, and they are allowed to discharge through a pipe 69 that is provided with a suitable valve to regulate their flow so as to maintain the concentrates discharging line at the top of the ore pulp in this compartment.

In the concentration of some particular characters of ores I have found in practice that the baffle plates can be dispensed with. This is particularly so when concentrating vanadium ores, and consequently my invention contemplates the use of the receiving, mixing and circulating mechanism either with or without them.

My oil flotation ore concentrating apparatus provides a positive, rapid, ore pulp and oil and air mixing and recirculating mechanism, that results in a very high recovery of the mineral values from ores; and while I have illustrated and described the preferred construction and arrangement of my invention, I do not wish to be limited to it, as many changes might be made

without departing from the spirit of my invention:

Having described my invention, what I claim as new and desire to secure by Letters Patent, is:

1. An oil flotation ore pulp concentrating apparatus comprising an ore pulp agitating compartment, a submerged, fixed ore pulp receiving cylinder in the agitating compartment and a rotary mixing cylinder adjoining and in axial line with the receiving cylinder and adapted to draw ore therefrom by suction force, and being provided with peripheral ore discharging apertures, means for rotating said mixing cylinder, and a pipe for feeding ore to the receiving cylinder.
2. An oil flotation ore concentrating apparatus, comprising means including ore pulp receiving, centrifugal and suction action members, and means including a screened ore pulp and air admitting member and a valve controlled air inlet member connected to the suction member and adapting the same to automatically draw an ample supply of air from the atmosphere by suction.
3. An oil flotation ore concentrating apparatus, comprising an agitating compartment provided with means including a rotating shaft, a fixed ore pulp and oil and air receiving cylinder and a rotating centrifugally operating mixing and circulating cylinder mounted on said shaft, and means including valve controlled air intake members extending into the atmosphere and connected to said fixed ore pulp receiving and said mixing cylinders, said ore pulp oil and air mixing and circulating apparatus being arranged to automatically draw a predetermined and regulated amount of air from the atmosphere by suction, a screened ore pulp pipe extending from said fixed ore pulp receiving cylinder to the level of the ore pulp in said agitating compartment adapted to permit any excess flow of ore pulp to flow back into said fixed ore pulp receiving cylinder, said screen being arranged to exclude the oil froth on the surface of said ore pulp in said agitating compartment from flowing into said pipe.
4. In an apparatus of the character described, the combination with an agitating tank, of a submerged ore pulp receiving cylinder in said tank, said ore pulp receiving cylinder comprising a cylindrical open ended stationary member, having a semi-circular row of inlet holes in its upper portion, an inlet pipe extending from said receiver to the water level of the tank, a screen on the water level end of said pipe, adapted to admit ore pulp to said pipe, but to exclude the oil froth therefrom, a valved air pipe secured to said screen and extending up into

the atmosphere above the ore pulp, a pipe extending from said receiver to the bottom portion of the tank, means for drawing the ore pulp from the receiver and discharging it in the surrounding body of water, and an ore pulp inlet feed pipe for the ore pulp receiver.

5. In an apparatus of the character described, the combination with an agitating tank, of a submerged receiving cylinder in the agitating tank, a rotatable agitating cylinder in axial line with and communicating with the receiving cylinder, having peripheral apertures and adapted to draw material from the receiving cylinder and expel it through said apertures into the agitating tank, a feed hopper and a pipe connecting the same with the receiving cylinder, and means for admitting air to the receiving cylinder.

6. In an apparatus of the character described, the combination with an agitating tank, of a stationary submerged receiving cylinder in said tank, a pipe for feeding material to the receiving cylinder, and a pipe for admitting air to the receiving cylinder, a rotary bladed agitating cylinder adjoining and in axial line with the receiving cylinder, having peripheral apertures, and being arranged to draw the material from the receiving cylinder by suction force and discharge it through the said apertures into the agitating tank, a valved pipe leading from the bottom of the settling tank, and a pipe leading from the receiving cylinder to the bottom of the agitating tank.

7. In an apparatus of the character described, the combination with an agitating tank, of a submerged stationary receiving cylinder in the agitating tank, an agitating cylinder in axial line with the receiving cylinder and adjoining the same, and having a plurality of apertures extending through its wall, a power driven shaft extending loosely through the receiving cylinder but rigidly connected to the agitating cylinder, said cylinder acting to draw material from the receiving cylinder and discharge it into the agitating tank, a pipe for feeding material to the receiving cylinder, a pipe leading from the receiving cylinder to the water line of the tank, a screen on said pipe, a valved pipe for admitting air to the screened pipe, and a pipe connecting the receiving cylinder with the bottom portion of the agitating tank.

In testimony whereof I affix my signature in presence of two witnesses.

ORREN ALLEN.
